UNITED STATES PATENT OFFICE.

CHARLES L. MAYHEW, OF NEWARK, NEW JERSEY.

DESIGN FOR A CYLINDER-PIECE FOR TRIPLE-CYLINDER ENGINES.

SPECIFICATION forming part of Design No. 31,411, dated August 15, 1899.

Application filed July 21, 1899. Serial No. 724,663. Term of patent 14 years.

To all whom it may concern:

Be it known that I, CHARLES L. MAYHEW, a citizen of the United States, and a resident of Newark, in the county of Essex and State of New Jersey, have invented a certain new and useful Design for a Cylinder-Piece for Triple-Cylinder Engines, of which the following is a specification, reference being had to the accompanying drawings, forming part of the same, in which—

Figure 1 is a front end view in perspective of a cylinder-piece embodying my new design, and Fig. 2 is a rearward end view in perspective of the same.

The cylinder-piece comprises three hollow cylinders A, B, and C, which are of substantially equal lengths and one of which, B, is of somewhat greater diameter than the others and which are arranged side by side in succession parallel to each other, with the larger cylinder B between the others, the said cylinders having near their forward open ends a substantially uniform radially-extended external flange D, concentric to the several cylinders, at the opposite sides of the described group thereof, and forming a web at d d' between the adjacent sides of the cylinders, near their forward ends, and a casing E, which has a substantially plane-face front side wall e, the area of which is greater than that of the described group of cylinders and with which side wall and about centrally of the area of its front side the rearward ends of the said several cylinders meet substantially at right angles, with their respective bores extending through said wall, the said casing E having a plane-face top e' and substantially plane-face end walls e² e³, respectively, at right angles to its front side wall e, a plane-face bottom, the rearward portion e' of which is at right angles to said front side wall and the forward portion e⁴ of which is upwardly inclined to its meeting with the lower edge of said front side wall, and substantially plane-face partitions e⁵ e⁶, extending between the top and the bottom of the casing at points between the adjacent bore-apertures of the said cylinders in said front side wall, the casing being open at its rearward side and having concave plates e⁸, arranged in the same

axial line on the rearward edges of the end walls e² e³ and of the partitions e⁵ e⁶, together with a semicylindrical forwardly-extending projection e⁹ on one end of the casing at its front side and cylindrical projections e¹⁰ e¹¹, 55 extending in the same axial line from the upper part of either end of the casing, near the front side thereof.

The essential features of the described design for a cylinder-piece are three hollow cylinders of substantially equal lengths and one of which is of somewhat greater diameter than the others and which are arranged side by side in succession, parallel to each other, with the larger cylinder between the smaller ones, the cylinders having near their forward open ends a substantially uniform radially-extended external flange which is concentric to the several cylinders, at the opposite sides of the described group thereof, and forms a web between the adjacent sides of the cylinders, near their said forward ends, and a casing having a substantially plane-face front side wall, the area of which is greater than that of the group of cylinders and with which side wall and about centrally of its front side the rearward ends of the said several cylinders meet substantially at right angles, with their respective bores extending through said wall, and the said casing having a plane-face top and substantially plane-face end walls, respectively, at right angles to its front side wall, a plane-face bottom, the rearward portion of which is at right angles to said front side wall and a forward portion of which is upwardly inclined to its meeting with the lower edge of said front side wall, and substantially plane-face partitions extending between the top and bottom of the casing at points between the adjacent bore-apertures of the said cylinders in said front side wall, the said casing being open at its rearward side and having concave plates arranged in the same axial line on the rearward edges of said end walls and said partitions, together with a semicylindrical forwardly-extending projection on one end of the casing, at its front side, and cylindrical projections extending in the same axial line from the upper part of either end of the casing, near the front side 100

thereof, all substantially as shown and described.

What I claim as my invention, and desire to secure by Letters Patent, is—

5 The design for a cylinder-piece for triple-cylinder engines herein shown and described.

Signed at New York, in the county of New

York and State of New York, this 14th day of July, A. D. 1899.

CHARLES L. MAYHEW.
